UNITED STATES PATENT OFFICE.

HARRY FRIEDMAN, OF LOS ANGELES, CALIFORNIA, ASSIGNOR TO ARCHITECTURAL IRON WORKS, OF LOS ANGELES, CALIFORNIA, A CORPORATION OF CALIFORNIA.

DESIGN FOR AN ELECTRIC-LIGHTING FIXTURE.

Application filed July 30, 1926. Serial No. 18,541. Term of patent 3½ years.

To all whom it may concern:

Be it known that I, HARRY FRIEDMAN, a citizen of Lithuania (having declared his intention of becoming a citizen of the United States), residing at Los Angeles, in the county of Los Angeles, State of California, have invented a new, original, and ornamental Design for Electric-Lighting Fixtures, of which the following is a specification, reference being had to the accompanying drawing, forming a part thereof.

In the drawing, Fig. 1 is a front elevation showing in full lines a fixture embodying my new design and in dotted lines the lighting elements; and Fig. 2 is a side elevation of the same.

I claim:

The ornamental design for an electric lighting fixture as shown.

HARRY FRIEDMAN.
